UNITED STATES PATENT OFFICE.

WILLIAM S. BATES, OF CHICAGO, ILLINOIS.

DESIGN FOR A PUZZLE.

SPECIFICATION forming part of **Design No. 22,479, dated May 30, 1893.**

Application filed December 1, 1892. Serial No. 453,782. Term of patent 7 years.

To all whom it may concern:

Be it known that I, WILLIAM S. BATES, of Chicago, Illinois, have invented and produced a new and original Design for a Puzzle, where-
5 of the following is a specification.

My design consists of a bar with enlarged ends, and three rings,—one of which is larger than the other two,—mounted upon the bar between its ends.

10 In the drawing, which is a face view of the puzzle, 1, 2 and 3, are the rings; 4 is the bar and 5 the enlarged ends of the bar. The in-

ternal diameter of the large ring 1 is equal to the diameter of the ends 5, while the internal diameter of the smaller rings 2 and 3, is less ¹⁵ than the diameter of the said ends.

I claim—

The design for a puzzle herein shown and described.

WM. S. BATES.
